(57) **CLAIM**

I claim, the ornamental design for a lid for a beverage container, as shown and described.

DESCRIPTION

FIG. 1 is a top perspective view of a lid for a beverage container shown in an environment of use;

FIG. 2 is a front elevation view thereof, shown separately for clarity of disclosure;

FIG. 3 is a back elevation view thereof;

FIG. 4 is a top plan view thereof;

FIG. 5 is a bottom plan view thereof;

FIG. 6 is a right-side elevation view thereof; and,

FIG. 7 is a left-side elevation view thereof.

The beverage container shown in FIG. 1 illustrates environment and forms no part of the claimed design. The portions of the lid for a beverage container shown in broken lines form no part of the claimed design.
